AUDIO-FILTER EDUCATIONAL BOARD

Jack N. Holcomb, Fort Lauderdale, Fla., assignor to
National Intelligence Academy

Filed Oct. 15, 1974, Ser. No. 514,900

Term of patent 14 years

Int. Cl. D19—07

U.S. Cl. D19—64

FIG. 1

FIG. 2

FIG. 3

FIG. 1 is a front perspective view of an audio-filter educational board showing my new design;

FIG. 2 is a left front perspective view thereof shown on a slightly reduced scale; and

FIG. 3 is a rear perspective view thereof.

I claim:

The ornamental design for an audio-filter educational board, as shown and described.
